(57) CLAIM

I claim the ornamental design for a ring incorporating a compartment for a pill, as shown and described.

DESCRIPTION

FIG. 1 is a perspective view of a ring incorporating a compartment for a pill, showing my new design;

FIG. 2 is a front elevational view thereof, the rear elevational view being a mirror image of this Figure;

FIG. 3 is a left side elevational view thereof; the right side elevational view being a mirror image of this Figure;

FIG. 4 is a top plan view thereof; and,

FIG. 5 is a bottom plan view thereof.

1 Claim, 2 Drawing Sheets

FIG. 1.

FIG. 2.

FIG. 3.

FIG. 4

FIG. 5.
